UNITED STATES PATENT OFFICE.

JOHN E. ROBBINS, OF GREENSBURG, AND WILLIAM A. KIRKPATRICK AND CLIFFORD P. KIRKPATRICK, OF INDIANAPOLIS, INDIANA.

TROLLEY-HEAD.

No. 921,650.

Specification of Letters Patent.

Patented May 11, 1909.

Application filed February 8, 1908. Serial No. 414,952.

To all whom it may concern:

Be it known that we, JOHN E. ROBBINS, a citizen of the United States, residing at Greensburg, in the county of Decatur, State 5 of Indiana, and WILLIAM A. KIRKPATRICK and CLIFFORD P. KIRKPATRICK, citizens of the United States, residing at Indianapolis, Marion county, State of Indiana, have invented certain new and useful Improvements 10 in Trolley-Heads, of which the following is a specification.

Our invention relates to an improved trolley head provided with means for assisting in the replacement of the trolley wheel on 15 the wire said means also serving to reduce the liability of displacement due to inequalities of the trolley wire or of the motion of the car.

The accompanying drawings illustrate our 20 invention.

Figure 1 is a side elevation of a trolley head constructed in accordance with our invention; Fig. 2 a plan; Fig. 3 an end elevation in half vertical section; Fig. 4 a vertical section 25 showing the positions assumed by the parts when the trolley wheel is drawn away from the trolley wire; Fig. 5 a vertical sectional detail on line 5 5 of Fig. 2.

In the drawings 10 indicates a harp or 30 head casting having formed in the fingers thereof a pair of substantially vertical guideways 11 in each of which is mounted a sliding head 12 each of said heads being normally urged upwardly to one extreme of the guideway by a light spring 13. Secured in the head 12 and extending transversely between the fingers of the harp 10 is a journal pin 14 upon the middle of which is journaled a trolley wheel 15 of any desired type. The ends 35 14' of pin 14 which are secured in the blocks 12 are preferably slightly ensmalled and this ensmalled portion has a length somewhat greater than the thickness of the block 12 so that there may be journaled thereon between 40 each side of the trolley wheel 15 and the adjacent block 12 a guard finger 16 the end of which is outwardly flared as clearly shown in Fig. 2. At the inner end of this finger 16 is a short finger 17 which is outwardly displaced 45 relative to the general plane of the finger 16 and arranged beneath a pin 18 on the adjacent arm of the harp 10 and normally in engagement with the finger 17. Arranged in 50 the path of possible movement of each finger

17 is a spring 19 each of said springs being 55 secured to the adjacent block 12.

In order to obtain the proper electrical connection with the trolley wheel we provide a sheet metal yoke 20 the ends of which are slipped over pin 14 closely adjacent the hub 60 ends of the trolley wheel 15 and this yoke is secured at its base or middle to one end of a U-shaped spring 21 the opposite end of said spring being secured in the throat of the harp 10. When the trolley wheel is in engagement 65 with the trolley wire 25 as shown in Fig. 1, the weight of the rearwardly projecting ends of the fingers 16 cause the fingers 17 thereof to remain in engagement with their pins 18 and the springs 13 will be compressed 70 until the blocks 12 come to rest against the shoulders 26 formed at the lower ends of the guideways 11, this compression of the springs 13 being due to the fact that such springs are 75 comparatively light and of course materially weaker than the spring which is commonly used to hold a trolley pole in operative position. So soon as the harp 10 tends to move downward however so as to withdraw the trolley wheel 15 from the trolley wire 25 the 80 springs 13 serve to urge the blocks 12 upwardly in their guideways 11. This movement causes the arms 17 of fingers 16 to be 85 swung downwardly by their coaction with pins 18, and fingers 16 are thus swung upwardly toward the position shown in full lines in Fig. 4, thus producing a comparatively wide and flaring throat immediately 90 above the trolley wheel so as to prevent many displacements of the trolley wheel and to facilitate replacing.

If the trolley head should be drawn down away from the trolley wire to the position shown in Fig. 4 where the upper ends of fingers 16 are still in position to be engaged 95 by any cross wires, a backward movement of the car will not injure the structure because the fingers 16 are free to be displaced, through the positions shown in dotted lines in Fig. 4, against the action of the springs 19 100 but as soon as such springs are flexed by such action they will immediately serve to snap the fingers 16 back past the vertical center so that said arms will resume the position shown in Fig. 1, the trolley wheel being in 105 engagement with the trolley wire.

We claim as our invention:—

1. The combination with the main head of

a trolley, of a contact carrying member mounted therein and substantially vertically movable therein, yielding means for urging said contact member to its upper position in 5 the head, a pair of pivoted fingers arranged adjacent said movable member, means for causing a swinging of said fingers by a movement of the contact member in the main head, and yielding means arranged in the 10 path of movement of said fingers to engage the same when in abnormal position and return them to normal.

2. The combination with the main trolley head, of a pair of blocks substantially vertically movable therein, springs for yieldingly urging said blocks to their upward position, 15 a cross pin carried by said blocks, a trolley wheel journaled thereon, a pair of fingers pivoted on said cross pin and each having an 20 outwardly flared rear end and an inner finger,

pins carried by the main head for engaging said inner fingers to swing said pivoted fingers by movement of the blocks in the main head, and returning springs 19 arranged in the path of movement of the piv- 25 oted fingers.

In witness whereof, we have hereunto set our hands at Hot Springs, Arkansas, and Indianapolis, Indiana, respectively.

JOHN E. ROBBINS.

WILLIAM A. KIRKPATRICK.

CLIFFORD P. KIRKPATRICK.
